Primary Examiner — Marie D. Fast Horse*Assistant Examiner* — Jennifer Sierra Yosinski(74) *Attorney, Agent, or Firm* — Cislo & Thomas, LLP(57) **CLAIM**

The ornamental design for a revolving shelf, as shown and described.

DESCRIPTION

FIG. 1 is a right side perspective view of a revolving shelf; FIG. 2 is a left side perspective view thereof;

FIG. 3 a top view thereof;

FIG. 4 is a bottom view thereof;

FIG. 5 is a front view thereof;

FIG. 6 is a rear view thereof;

FIG. 7 is a right side view thereof; and,

FIG. 8 is a left side view thereof.

The broken lines shown in the drawings depict portions of the revolving shelf that form no part of the claimed design.

1 Claim, 8 Drawing Sheets(56)
